United States Patent Office.

T. A. MACAULAY, OF NORTHAMPTON, MASSACHUSETTS.

Letters Patent No. 100,909, dated March 15, 1870.

IMPROVEMENT IN NEEDLE-ADJUSTING BLOCK FOR SEWING-MACHINES.

The Schedule referred to in these Letters Patent and making part of the same.

To all whom it may concern:

Be it known that I, T. A. MACAULAY, of the town of Northampton, county of Hampshire, and Commonwealth of Massachusetts, have invented a new and improved Adjustable Needle-Block for Sewing-Machines; and I do hereby declare that the following is a full, clear, and exact description thereof, which will enable others skilled in the art to make and use the same, reference being had to the accompanying drawings forming part of this specification.

The nature of my invention relates to an improved manner of adjusting the needle in a sewing-machine, so as to bring it toward or from the shuttle or hook, as the case may require; and

It consists in constructing on the needle-block, at right angles to the line of the needle-hole, a stem, through which a set-screw is passed for confining the needle, the stem passing through a hole near the lower end of the needle-bar, which latter is reduced and slotted, and across which slot a clamping-screw passes, the block being steadied by a pin projecting from the needle-bar and fitting in a groove in its top.

Figure 1 is a vertical side view, showing the needle-bar *h*, the head of the clamping-screw *f*, the set-screw *b* for securing the needle, the needle-block *a*, and stem *a'*, passing through the hole in the needle-bar, the needle *c*, and steady-pin *e*.

Figure 2 is a vertical face view of fig. 1, showing the

slot *i* and clamping-screw *f*, steady-pin *e*, and needle-bar *h*.

Figure 3 is a view of figs. 1 and 2 from above.

Similar letters in these figures refer to like parts.

The stem *a'* of the needle-block *a* is inserted into the hole in the needle-bar *h*, which it fits accurately; is maintained in a vertical position by the steady-pin *e* resting in a groove at the top in the needle-block, and firmly secured in any required position by the clamping-screw *f* at the lower end of the needle-bar.

g is a guide-hole for the passage of the thread to the needle, and

d, a set-screw, for making a fine adjustment of the block.

Figures 4 and 5 show a modification, in which the steady-pin and set-screw are combined in one, and represented by the letter *x*.

Having thus fully described my invention,

What I claim, and desire to secure by Letters Patent, is—

The needle-bar having the hole, slot, steady-pin, and clamping-screw, in combination with the block provided with the stem and groove, as and for the purpose set forth.

T. A. MACAULAY.
